CLAIM

The ornamental design for a warning light for emergency vehicles, as shown and described.

DESCRIPTION

FIG. 1 is a reduced perspective view of a warning light assembly for emergency vehicles showing my new design, with the cord broken away to indicate indeterminate length;

FIG. 2 is a front elevational view thereof;

FIG. 3 is a rear elevational view thereof;

FIG. 4 is a top plan view thereof, with the cord omitted;

FIG. 5 is a side elevational view thereof, with the opposite side being a mirror image; and,

FIG. 6 is a bottom plan view thereof, with the cord omitted.

FIG. 1

FIG. 6

FIG. 2

FIG. 3

FIG. 4

FIG. 5
